UNITED STATES PATENT OFFICE.

HIDALGO MOYA, OF LEICESTER, ENGLAND.

TYPE-WRITER.

No. 876,989.

Specification of Letters Patent.

Patented Jan. 31, 1908.

Application filed February 25, 1907. Serial No. 359,180.

To all whom it may concern:

Be it known that I, HIDALGO MOYA, a citizen of the United States of America, residing at Leicester, in the county of Leicestershire, England, have invented certain new and useful Improvements in Type-Writers, of which the following is a specification.

This invention relates to improvements in typewriters of the type-cylinder class, the object being to render the construction simpler and more economical.

In my United States Patent No. 752795, I have described a typewriter, in which a cylinder type-carrier is carried in a swinging frame so that the cylinder can be rotated to select the type or rocked to effect the printing operation. The rotation was caused by a cam engaging projections shifted by the key-levers, and the selection of the type was effected by disengaging the cam from the cylinder by a clutch and by the engagement of a crown-wheel on the cylinder-spindle with a projection. The arrangement of the cam and of the sliding pins which operate the same is similar to that employed on my well-known machine.

The present improvements relate particularly to the method of determining the extent to which the type-cylinder is rotated by the operation of the various key-levers, to the method of permitting and effecting the movement of the swinging frame at the printing operation, and to the method of preventing rotation of the type-cylinder and thus fixing with precision its position during the printing operation.

According to this invention in combination with a cam actuating the type-cylinder, and a pivoted cam-operating frame actuating pins engaging the cam, I employ key-levers each having one abutment arranged to move the pivoted cam-operating frame, and a second abutment so shaped and arranged as to arrest the movement of the said frame when the cam has been turned to the required extent.

In order to effect the printing operation, the swinging frame carrying the cylinder and cam has a toothed pinion thereon, and a pivoted main frame which supports the cam-operating frame carries a toothed segment which by engagement with the pinion shifts the swinging frame when the desired type has been selected.

In order to insure that the cam-operating frame shall be shifted to the required extent

before the printing operation begins, the main frame is normally locked by a catch, and a cam-shaped projection on a movable universal bar extending across beneath all the key-levers is arranged automatically to withdraw the catch when the selecting movement of the cam-operating frame is completed, whereupon the main frame is free to move and to effect the printing operation.

To fix with precision the position of the type-cylinder during a printing operation, the type-cylinder and cam are mounted on one spindle carried in the swinging frame and a toothed or notched disk on the spindle is arranged to engage a fixed knife-edge when the swinging frame moves.

In the accompanying drawings, which illustrate that portion of a typewriter to which this invention relates:—Figure 1 is a side view of the mechanism in its normal position; Fig. 2 shows the same when the key lever has been depressed sufficiently to select the type; and Fig. 3 shows the same when the key lever has been depressed to effect the printing operation. Fig. 4 is a plan view, partly in section, of the cam-operating frame and cam and contiguous parts, and Fig. 5 is a perspective view of the parts seen in Fig. 4.

Like letters indicate like parts throughout the drawings.

The type-carrying cylinder A is mounted on a spindle A¹ which also carries the cam B and the spindle is rotatably mounted in a swinging frame C supported on trunnions C¹ in the framework of the typewriter. The cam B is caused to rotate by the sliding arms and tailpieces as hitherto employed on my well-known machine. These arms are engaged by the forked end D¹ of a cam-operating frame D pivoted at D² to a main frame E, and the forked end is normally kept in its lowest position by a spring D³. There are two cam-operating frames D, one for each side of the typewriter. Referring to Figs. 4 and 5 the cam-operating frame D has a forked end D¹ which engages a pin B¹ having a projection B² engaging with a slot in the cam B. The pin B¹ and projection B² are arranged to slide vertically in guides B³ and thus when the frame D tilts on its pivot to a certain extent, the projection B² is raised and the cam B turned to a corresponding extent. The main frame E is pivoted on a fixed rod F and carries a toothed segment E¹ engaging with a toothed pinion C¹ on the trunnion C¹.

of the swinging frame C; and a spring C³ between the frame C and a fixed bar C⁴ normally maintains the frame C in the position shown in Figs. 1 and 2, a fixed stop C⁵ being arranged to limit the backward movement of the swinging frame C.

In order to insure that upon the depression of a key-lever the cam-operating frame D shall be shifted to the required extent before 10 the main frame E is moved to effect the printing operation, the main frame E is normally locked by a catch G sliding in guides on the framework of the machine and controlled by a spring G¹. A movable universal bar G² 15 extends across beneath all the key-levers H and carries a cam-shaped projection G³ which (when the cam-operating frame D is properly shifted) engages a projection G⁴ on the catch G and thus liberates the main 20 frame E. The projection G⁴ may consist of a stud screwed into the catch G, or it may be otherwise adjustable.

The key-levers H are pivoted on the rod F and controlled by springs J connected to a 25 fixed rod J¹, and a fixed bar K determines the normal position of the key-levers. Each key-lever has one abutment H¹ arranged to engage a transverse bar D⁴ at one end of the frame D when the key is depressed so as to 30 move the frame D, and another abutment H² of such a length and so arranged as to engage a transverse bar D⁵ at the other end of the frame D and arrest the movement of the frame when the roller A has been turned to 35 the required extent. The abutments H² and H¹ on the various levers are of different lengths for this purpose, and the transverse bar D⁵ is so arranged in relation to the abutments H² that it only engages an abutment 40 when the corresponding lever H is depressed.

The movement of the key-lever from the position shown in Fig. 1 to that shown in Fig. 2, rotates the cam B and the roller A to the required extent, and, at the point shown in 45 Fig. 2, the catch G is withdrawn from the main frame E. Further movement of the key-lever to the position shown in Fig. 3 causes the cam-operating frame D to pull down the main frame E, thereby turning the 50 toothed segment E¹ and swinging the frame C on its trunnions C¹ and effecting the printing operation.

A toothed notched disk or wheel L is fixed at the bottom of the spindle A¹, and, when 55 the frame C swings, this engages the fixed knife-edge M and determines with precision the position of the cylinder A. The mechanism for shifting the cylinder A longitudinally for operating the carriage and other parts of 60 the typewriter, form no part of this invention and have not been referred to or illustrated.

It is to be understood that the details of arrangement and construction may be varied 65 without departing from this invention.

What I claim as my invention and desire to secure by Letters Patent is:—

1. In a typewriter of the type-cylinder class the combination of a swinging frame supported on trunnions in the typewriter, a type-cylinder rotatably mounted in said swinging frame, a pivoted frame operatively connected with the type-cylinder, means for rotating the type-cylinder as said pivoted frame tilts on its pivot without imparting movement to the swinging frame, and key-levers each having one abutment arranged to engage and tilt said pivoted frame and a second abutment arranged to engage and arrest the tilting of said pivoted frame when the type-cylinder is turned to the required extent. 75

2. In a typewriter of the type-cylinder class the combination of a swinging frame supported on trunnions in the typewriter, a type-cylinder rotatably mounted in said swinging frame, a main frame pivoted in the typewriter, a cylinder-rotating frame operatively connected with the type cylinder and pivoted on said main frame by a pivot which moves with said main frame, means for rotating the type-cylinder as the cylinder-rotating frame tilts on its pivot without imparting movement to the swinging frame, key-levers each having one abutment arranged to engage and tilt said frame and a second abutment arranged to engage and arrest the tilting of said frame when the type-cylinder is turned to the required extent, and means actuated by the key-levers for shifting the main frame and the swinging frame when the type-cylinder is turned to the required extent. 90

3. In a typewriter of the type-cylinder class the combination of a swinging frame supported on trunnions in the typewriter, a type-cylinder rotatably mounted in said swinging frame, a main frame pivoted in the typewriter, a cylinder-rotating frame pivoted on said main frame by a pivot which moves with said main frame and operatively connected with the type cylinder, means for rotating the type-cylinder as the cylinder-rotating frame tilts on its pivot without imparting movement to the swinging frame, key-levers each having one abutment arranged to engage and tilt said frame and a second abutment arranged to engage and arrest the tilting of said frame when the type-cylinder is turned to the required extent, means actuated by the key-levers for shifting the main frame and the swinging frame when the type-cylinder is turned to the required extent. 105

4. In a typewriter of the type cylinder class the combination of a swinging frame supported on trunnions in the typewriter, a type-cylinder rotatably mounted in said swinging frame, a main frame pivoted in the typewriter, a cylinder-rotating frame pivoted 120

on said main frame by a pivot which moves with said main frame and operatively connected with the type-cylinder, means for rotating the type-cylinder as the cylinder-rotating frame tilts on its pivot without imparting movement to the swinging frame, key-levers each having one abutment arranged to engage and tilt said frame and a second abutment arranged to engage and arrest the tilting of said frame when the type-cylinder is turned to the required extent, means actuated by the key-levers for shifting the main frame and the swinging frame when the type-cylinder is turned to the required extent, means for locking the main frame until the type-cylinder is turned to the required extent, a notched disk operatively connected to the type-cylinder and on the opposite side of the trunnion therefrom and a fixed projection arranged to engage the notched disk when the swinging frame is shifted to determine with precision the position of the type-cylinder.

5. In a typewriter of the type-cylinder class the combination of a swinging frame carrying the type-cylinder and an actuating cam therefor, a toothed pinion on the swinging frame, a pivoted main frame having a toothed segment engaging said toothed pinion, a cam operating frame pivoted on said main frame by a pivot which moves with said main frame, and key-levers each having one abutment arranged to engage and tilt the pivoted cam-operating frame and a second abutment to engage and arrest the tilting of said cam-operating frame when the cam has been turned to the required extent.

6. In a typewriter of the type-cylinder class the combination of a swinging frame supported on horizontal trunnions in the typewriter, a toothed pinion on said trunnions, a spindle rotatably mounted in said swinging frame, a type-cylinder and an actuating cam therefor both on said spindle, a main frame pivoted in the typewriter, a toothed segment on said main frame engaging said toothed pinion, a cam-operating frame pivoted to said main frame, means for rotating the cam when the cam-operating frame is tilted, and key-levers pivoted in the typewriter each having one abutment arranged to engage and tilt the cam-operating frame when the key is depressed and a second abutment arranged to engage and arrest the tilting of the cam-operating frame when the cam is turned to the required extent.

7. In a typewriter of the type-cylinder class the combination of a swinging frame supported on horizontal trunnions in the typewriter, a toothed pinion on said trunnions, a spindle rotatably mounted in said swinging frame, a type-cylinder and an actuating cam therefor both on said spindle, a main frame pivoted in the typewriter, a

toothed segment on said main frame engaging said toothed pinion, a cam-operating frame pivoted to said main frame, means for rotating the cam when the cam-operating frame is tilted, key-levers pivoted in the typewriter each having one abutment arranged to engage and tilt the cam-operating frame when the key is depressed and a second abutment arranged to engage and arrest the tilting of the cam-operating frame when the cam is turned to the required extent, and means for locking the main frame until the cam is turned to the required extent.

8. In a type-writer of the type-cylinder class the combination of a swinging frame supported on horizontal trunnions in the type-writer, a toothed pinion on said trunnions, a spindle rotatably mounted in said swinging frame, a type-cylinder and an actuating cam therefor both on said spindle, a main frame pivoted in the typewriter, a toothed segment on said main frame engaging said toothed pinion, a cam-operating frame pivoted to said main frame, means for rotating the cam when the cam-operating frame is tilted, key-levers pivoted in the typewriter each having one abutment arranged to engage and tilt the cam-operating frame when the key is depressed and a second abutment arranged to engage and arrest the tilting of the cam-operating frame when the cam is turned to the required extent, a spring-controlled sliding catch normally locking the main frame, a vertically-movable horizontal bar extending under all the key-levers, and a cam-shaped projection on said bar arranged to withdraw said catch from the main frame when the cam is turned to the required extent.

9. In a typewriter of the type-cylinder class the combination of a swinging frame supported on horizontal trunnions in the typewriter, a toothed pinion on said trunnions, a spindle rotatably mounted in said swinging frame, a type-cylinder and an actuating cam therefor both on said spindle, a main frame pivoted in the typewriter, a toothed segment on said main frame engaging said toothed pinion, a cam-operating frame pivoted to said main frame, means for rotating the cam when the cam-operating frame is tilted, key-levers pivoted in the typewriter each having one abutment arranged to engage and tilt the cam-operating frame when the key is depressed and a second abutment arranged to engage and arrest the tilting of the cam-operating frame when the cam is turned to the required extent, a spring-controlled sliding catch normally locking the main frame, a vertically-movable horizontal bar extending under all the key-levers, a cam-shaped projection on said bar arranged to withdraw said catch from the main frame when the cam is turned to the required extent, a notched

disk fixed at the bottom of the type-cylinder spindle and a fixed knife-edge so arranged as to engage the disk when the swinging frame is shifted to determine with precision the position of the type-cylinder.

10. In a typewriter of the type-cylinder class the combination of a spring-controlled, swinging frame supported on horizontal trunnions in the typewriter, a toothed pinion 10 on said trunnions, a spindle rotatably mounted in said swinging frame, a type-cylinder and an actuating cam therefor both on said spindle, a main frame pivoted in the typewriter, a toothed segment on said main 15 frame engaging said toothed pinion, a spring-controlled cam-operating frame pivoted to said frame, means for rotating the cam when the cam-operating frame is tilted, spring-controlled key-levers pivoted in the typewriter each having one abutment arranged to engage and tilt the cam-operating frame when the key is depressed and a second abutment arranged to engage and arrest the tilting of the cam-operating frame when the cam 25 is turned to the required extent, a spring-controlled sliding catch normally locking the main frame, a vertically-movable horizontal bar extending under all the key-levers, and a cam-shaped projection on said bar arranged 30 to withdraw said catch from the main frame when the cam is turned to the required extent.

11. In a typewriter of the type-cylinder class the combination of a spring-controlled 35 swinging frame supported on horizontal trunnions in the typewriter, a toothed pinion on said trunnions, a spindle rotatably mounted in said swinging frame, a type-cylinder and an actuating cam therefor both on said 40 spindle, a main frame pivoted in the typewriter, a toothed segment on said main frame engaging said toothed pinion, a spring-controlled cam-operating frame pivoted to said main frame, means for rotating the cam 45 when the cam-operating frame is tilted, spring-controlled key-levers pivoted in the typewriter each having one abutment arranged to engage and tilt the cam-operating frame when the key is depressed and a second 50 abutment arranged to engage and arrest the

tilting of the cam-operating frame when the cam is turned to the required extent, a spring-controlled sliding catch normally locking the main frame, a vertically-movable horizontal bar extending under all the key-levers, and a cam-shaped projection on said bar arranged to withdraw said catch from the main frame when the cam is turned to the required extent, a notched disk fixed at the bottom of the type-cylinder spindle and a 55 fixed knife-edge so arranged as to engage the disk when the swinging frame is shifted to determine with precision the position of the type-cylinder.

12. In a typewriter of the type-cylinder 60 class the combination of a type-cylinder, a pivoted frame operatively connected therewith, means for rotating the type-cylinder as the frame tilts on its pivot without imparting movement to the swinging frame and pivoted 65 key levers each having two abutments between the pivot and the key, one of said abutments arranged to engage and tilt said frame and the second abutment close to the key lever pivot arranged to engage and arrest the tilting of said frame when the type-cylinder is turned to the required extent, said frame being free to pass the second 70 abutments of the un-depressed key levers.

13. In a type-writer of the type-cylinder 75 class the combination of a rotatable type-cylinder, an actuating cam connected therewith, a pivoted cam-operating frame engaging said cam, and pivoted key levers each having two abutments between the 80 pivot and the key, one of said abutments arranged to engage and tilt the cam-operating frame and the second abutment close to the key lever pivot arranged to engage and arrest the tilting of the cam-operating frame 85 when the cam is turned to the required extent said frame being free to pass the second abutments of the un-depressed key levers.

In testimony whereof I have signed my name to this specification in the presence of 90 two subscribing witnesses.

HIDALGO MOYA.
